(57) **CLAIM**

The ornamental design for a measurement head for a surgical tool, as shown and described.

DESCRIPTION

FIG. 1 is a top, front left perspective view of a measurement head for a surgical tool;

FIG. 2 is a bottom, front, left perspective view thereof;

FIG. 3 is a top, rear left perspective view thereof;

FIG. 4 is a bottom, rear left perspective view thereof;

FIG. 5 is a top, front right perspective view thereof;

FIG. 6 is a bottom, front right perspective view thereof;

FIG. 7 is a top, rear right perspective view thereof;

FIG. 8 is a bottom, rear right perspective view thereof;

FIG. 9 is a front end view thereof;

FIG. 10 is a rear end view thereof;

FIG. 11 is a top plan view thereof;

FIG. 12 is a bottom plan view thereof;

FIG. 13 is a right side elevational view thereof; and,

FIG. 14 is a left side elevational view thereof.

In the drawings, the broken lines depicting portions of the measurement head for a surgical tool form no part of the claimed design.

1 Claim, 11 Drawing Sheets
